(57) **CLAIM**

The ornamental design for a trailer hitch protector, as shown and described.

DESCRIPTION

FIG. 1 is a perspective view of a trailer hitch protector, showing our new design, shown in its position of use; FIG. 2 is an enlarged right side elevation view thereof; FIG. 3 is an enlarged rear side elevation view thereof; FIG. 4 is an enlarged front side elevation view thereof; FIG. 5 is an enlarged left side elevation view thereof; FIG. 6 is an enlarged top plan view thereof; and, FIG. 7 is an enlarged bottom plan view thereof. The broken line showing of environment is for illustrative purposes only and forms no part of the claimed design.
